SURGICAL GARMENT

Esther K. McDowell, Minneapolis, Minn., assignor
to Esther K. Leggate, New Galilee, Pa.

Application February 4, 1948, Serial No. 6,251

1 Claim. (Cl. 2-27)

1

This invention has relation to a surgical or supporting garment in the nature of a corset.

An object of the invention is to provide a surgical or supporting garment of new and improved construction adapted to the purpose of comfortably supporting the abdomen of a wearer.

A further object is to provide a garment of the present character which will incorporate desirable and improved features and characteristics of construction devised to be useful in the support of the abdomen of a wearer, as well as in the confining of the hips.

And a further object is to provide a surgical or supporting corset which will include features and characteristics as hereinafter set forth.

In the accompanying drawings forming a part of this specification,

Fig. 1 is a front elevational view of a surgical garment made according to the invention with parts situated as when applied to a wearer's body, hose supporting straps of the surgical garment being omitted;

Fig. 2 is a rear elevational view of the disclosure of Fig. 1;

Fig. 3 is a front elevational view of the surgical garment as when spread out flat;

Fig. 4 is a view corresponding generally with the disclosure of Fig. 3, but showing front side sections or flaps of the surgical garment situated as when applied to a wearer's body; and

Fig. 5 is a view corresponding generally with the disclosures of Figs. 3 and 4, but showing said front side sections or flaps and a belt or waist band of said surgical garment situated as when applied to a wearer's body.

The surgical garment includes rear side sections, denoted 10 and 11, respectively, the one right and the other left, having their interior edge portions joined to each other by adjustable lacing 30 extending longitudinally of said surgical garment for its full length and adapted to lie at the center of a wearer's back when the surgical garment is in applied position. Each of the rear side sections 10 and 11 will be of sufficient length to extend from position several inches above the waist line to position somewhat below the hips, and each of said rear side sections includes an interior longitudinally extending portion 12 adapted to be situated at the rear of a wearer and an exterior longitudinally extending portion 13 adapted to be situated at a side and over a hip of a wearer.

Front side sections or flaps, represented 14 and 15, respectively, join the exterior longitudinally

extending portions 13 of the rear side sections 10 and 11. Each of said front side sections or flaps has length in the disclosure as made which is coextensive with the length of the rear side section to which it is connected, and said rear side sections are of equal length. The front side sections or flaps 14 and 15 do not meet. Instead, they will be relatively situated about as disclosed in the drawings when the surgical garment is in applied position upon a wearer. See Fig. 4.

A belt or waist band 16, at an upper part of the front of the surgical garment and disposed forwardly or outwardly of the front side sections or flaps 14 and 15, includes opposite side edges which join upper parts of the exterior longitudinally extending portions 13 of said rear side sections 10 and 11. In the disclosure as made, the upper edge of said belt or waist band is intended to terminate at about the waist line, but could, however, terminate somewhat above the waist line. The lower edge of the center front of the belt or waist band 16 is intended to terminate at about the pubis bone, and the lower edge of said belt or waist band is downwardly curved to follow the contour of the lower portion of the abdomen in such manner that the belt or waist band can serve as an abdominal supporter. Said belt or waist band is constituted as two separate sections of material. More explicitly, the belt or waist band is openable at the left side of a wearer, its separate sections being fastened by disengageable hooks and eyes, indicated 17, which extend along a line disposed crosswise of said belt or waist band.

An auxiliary support includes a piece of non-elastic webbing having an intermediate part thereof secured, as at 18, to a lower midportion of the center front of the belt or waist band 16 and free end parts 19, 19 thereof at opposite sides of said midportion. The auxiliary support or non-elastic webbing is at and adjacent to the lower edge of said belt or waist band. The free end parts 19, 19 extend in direction toward the opposite ends of the belt or waist band 16 and terminate in considerably spaced relation to said opposite ends. Buckles secured upon the free end parts 19, 19 are designated 20, 20, and an adjusting strap, encircling the surgical garment and having its opposite ends removably assembled with said buckles 20, 20, is denoted 21. An intermediate portion of said adjusting strap 21 extends through loops 22 secured to the outer or rearward side of the interior longitudinally

extending portions 12 at elevation of the lower edge somewhat above the elevation of the belt or waist band 16.

The auxiliary support or non-elastic webbing may be of any shape considered desirable to care for various conditions, and may be cupped to greater or less extent to conform to the shape of padding at the inner side of the lower front of the belt or waist band ordinarily employed for lifting and holding up a falling stomach, commonly known as ptosis. It will be apparent that tightening of the adjustable strap 21 will cause the abdomen of a wearer of the surgical garment to be uplifted and supported.

A hip reducing means or thigh control, designated 23, at a lower part of the front of the surgical garment, below the belt or waist band 16 and disposed forwardly or outwardly of the front side sections of flaps 14 and 15, includes opposite side edges which join lower parts of the exterior longitudinally extending portions 13 of the rear side sections 10 and 11. The upper edge portion of said hip reducing means or thigh control 23 is adapted to overlie the lower edge portion of said belt or waist band 16 and underlie the free end parts of the auxiliary support or non-elastic webbing, and complementary snap fasteners 24, 24, upon an upper portion of an intermediate part of the hip reducing means or thigh control and the belt or waist band, are for detachably securing said hip reducing means or thigh control and said belt or waist band to each other. The lower edges of opposite end parts of the hip reducing means or thigh control 23 terminate at about the lower edges of the exterior longitudinally extending portions 13 of the rear side sections 10 and 11, and the lower edge of an intermediate part of said hip reducing means or thigh control is upwardly curved about as disclosed in the drawings. The hip reducing means or thigh control is constituted as three separate sections of material. More explicitly, said hip reducing means or thigh control is openable at the left side of a wearer, first and second of its separate sections, represented 25 and 26, respectively, being fastened together by disengageable hooks and eyes, designated 27, which extend along a line disposed crosswise of the hip reducing means or thigh control and a third of its separate sections, denoted 28, being adjustably fastened to the second separate section 26 by an adjustable elastic lacing cord 29 along a line disposed crosswise of said hip reducing means or thigh control. The first and third separate sections 25 and 28 are secured to the exterior longitudinally extending portions 13, 13 of the rear side sections 11 and 10, respectively, at the outer or forward sides of the front side sections or flaps 14 and 15, the elastic lacing cord 29 is adapted to be disposed centrally at the front of a wearer, directly opposite the adjustable lacing 30, and the complementary snap fasteners 24, 24 are situated at opposite sides of and adjacent to said elastic lacing cord 29, as well as at opposite sides of and adjacent to the attached part of the auxiliary support or non-elastic webbing, beneath the free end parts 19, 19.

The rear side sections 10 and 11 include usual boning or covered stays 31 extending substantially longitudinally of said rear side sections, and the belt or waist band 16 includes usual boning or covered stays 32 extending substantially transversely of said belt or waist band.

Hose supporting straps of the surgical garment are represented 33. Desirably, the hose

supporting straps can be applied to said surgical garment at about the locations as disclosed in the drawings. As shown, a pair of hose supporting straps extend downwardly from the lower edge of the belt or waist band 16, a single hose supporting strap extends downwardly from the lower edge of each of the front side sections or flaps, and a single hose supporting strap extends downwardly from the lower edge of each of the exterior longitudinally extending portions 13. In all, the illustrated embodiment of the invention incorporates six hose supporting straps 33.

The front side sections or flaps 14 and 15 are of sufficient widths at their lower portions to protect the thighs, and upper portions of said front side sections or flaps are adapted to lie beneath the hooks and eyes 17 which detachably connect the separable sections of the belt or waist band 16.

The belt or waist band 16 and the hip reducing means or thigh control 23 operate independently in the performance of their intended functions. Stated differently, said hip reducing means or thigh control, below the belt or waist band 16 and the auxiliary support, is for the accomplishment of an independent adjustment of the lower portion of the surgical garment.

The lacing at the back of the surgical garment is for accomplishing adjustment to the figure of a wearer, as well as for drawing in the abdomen, and the auxiliary support is adapted to be drawn inwardly and upwardly by the adjusting strap 21 to give additional abdominal support. By tightening of said adjusting strap, the weight of the abdomen can be supported by said auxiliary support and carried from the body of a wearer with distribution of the supporting effort across the back and over the hips of the wearer. At the same time, the lower portion of the belt or waist band 16, retained in abdominal supporting position by the auxiliary support, will constitute an entity through the medium of which said auxiliary support applies its supporting effort to the abdomen.

What is claimed is:

In a surgical garment of the type described, the combination of a pair of non-elastic rear side sections having opposing edges, an adjustable flexible lacing for positioning said opposing edges with respect to each other, front side flaps integrally connected to outer edges of said rear side sections from top to bottom of said sections, a non-elastic waist band integrally connected to said outside edges of said rear sections adjacent the connection of said front flaps thereto and extending from position near the top of said rear side sections to position near the center thereof, said waist band consisting of two separate pieces of material overlapping each other, means for detachably securing said separate overlapping pieces of said waist band to each other, a non-elastic auxiliary support having a central portion thereof secured to a central lower front portion of said waist band and having free end parts thereof extending outwardly from said central portion, an adjusting strap encircling the garment, means constituted as loops fixed to an outer surface of said rear sections above said auxiliary support for supporting said adjusting strap, means constituted as buckles secured to outer portions of said free end parts for adjustably fastening said strap with respect to said auxiliary support, a non-elastic thigh control member integrally connected to outer edges of said rear side sections adjacent the connection of said front

side flaps and extending from position slightly above a lower edge of said waist band to position adjacent the bottom of said rear side sections and consisting of two strips of material each having opposing edges spaced from the other strip edge and an adjustable elastic lacing for positioning said opposing edges with respect to each other, one of said strips of material making up said thigh control member consisting of two overlapping pieces, and means for detachably fastening said two overlapping pieces of said thigh control to each other.

ESTHER K. McDOWELL.
